UNITED STATES PATENT OFFICE.

CHARLES MAGEE, OF WILLIAMSBURG, NEW YORK, ASSIGNOR TO THE
BIGELOW CARPET COMPANY, OF CLINTON, MASSACHUSETTS.

DESIGN FOR A CARPET.

SPECIFICATION forming part of Design No. 12,430, dated August 23, 1881.

Application filed July 14, 1881. Term of patent 3½ years.

To all whom it may concern:

Be it known that I, CHARLES MAGEE, of Williamsburg, in the county of Kings and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The design consists in a series of vine-like branches bearing flowers, buds, and leaves, and running over a finely-checked background.

The group D consists of a vine bearing upon it the figure C, resembling an open flower. This group also contains the figure h, a flower with a curved stem projecting from its end, on which appears another leaf-like flower; also, the figure p, a bud-like figure, from which project two stems bearing buds or flowers. This group D is joined by a vine-stem to the figure A, resembling a leaf with finger-like projections, which is, in turn, connected to the figure e, consisting of three stems bearing upon them

figures resembling pin-wheels, above which projects a flower-like figure. This figure e is also connected by the vine-stem with the figure O—a fan-shaped projection from the stem—and with the figure f, which consists of an oblong open loop.

On a vine connecting the figures C and A appears the figure g—a knob-like projection.

The group E is composed of the figures f, o, and e, already described, and of the figure b, a stem of the vine bearing on its end bud-like figures; also, of the figure B—a fan-shaped figure projecting from the vine; of the figure d—a leaf-like figure; of the figure j—a branch with three circular flowers projecting upon separate stems; and of the figure a—a projection of the vine bearing flower-like figures and leaves.

I claim—

The design for carpets, consisting of the group D, containing figures C h p, figure A, and group E, containing figures f, b, g, B, e, o, j, a, and d, substantially as shown.

CHARLES MAGEE.
